UNITED STATES PATENT OFFICE.

WILLARD D. LOCKWOOD, OF SCHENECTADY, NEW YORK.

CONCRETE-BUCKET.

992,724.

Specification of Letters Patent. Patented May 16, 1911.

Application filed December 10, 1908, Serial No. 466,882. Renewed April 18, 1910. Serial No. 556,259.

To all whom it may concern:

Be it known that I, WILLARD D. LOCKWOOD, a citizen of the United States, residing at Schenectady, in the county of Schenectady, State of New York, have invented certain new and useful Improvements in Concrete-Buckets; and I do hereby declare the following to be a full, clear, and exact description of the invention, such as will enable others skilled in the art to which it appertains to make and use the same.

This invention relates to hoisting buckets of the dumping type and has especial reference to a bucket constructed for handling concrete and other cementitious material.

One object of the invention is to provide a bucket of such construction that the hinges will be kept free from concrete and the hinge portion of the dumping doors kept clean.

Another object of the invention is to so construct such a bucket that the concrete will have an unobstructed path when the bucket is dumped.

A third object of the invention is to provide a novel construction of bucket wherein the abutting edges of the doors will be automatically cleaned.

A fourth object of the invention is to provide a novel bail arrangement for such a bucket of improved character.

With the above and other objects in view, the invention consists, in general, of a bucket provided with bottom drop doors of novel construction together with a novel bail arrangement for supporting the bucket.

The invention further consists in certain improved arrangements of details and novel constructions of parts hereinafter fully described, illustrated in the accompanying drawings, and specifically set forth in the claims.

In the accompanying drawings, like characters of reference indicate like parts in the several views, and:—Figure 1 is a side elevation of a bucket constructed in accordance with this invention, the doors being shown in full lines as closed when the bucket is being hoisted and in dotted lines as closed when the bucket is set on a car or the like. Fig. 2 is a similar view showing the bucket open. Fig. 3 is an end elevation of the bucket with the doors open. Fig. 4 is a detail in section showing the hinge portion of the door and end wall.

The numeral 10 indicates the body of the bucket and this body is preferably of the usual form with parallel sides and ends that incline inward from top to bottom. Around the top and bottom of the bucket are the usual reinforcing bands 11.

Upon the end walls of the bucket are mounted angles 12 arranged in pairs and in spaced relation. These angles extend slightly below the bottom of the bucket as indicated at 13 and are there provided with suitable perforations to receive a hinge pin 14. In the form here shown, two pairs of these angles are used but it is obvious that as many pairs may be used as are required for the size of bucket used.

Doors 15 are arranged to close the bottom of the bucket and these doors have their sides and meeting edges provided with stiffening angles 16. Upon each of these doors are mounted tee irons 17 which are so positioned that the web of the iron extends between the angles 12, and this web is provided with a suitable perforation to receive the pin 14 which passes through those angles. The door plate is provided at that part which is adjacent the end wall of the bucket with a meeting edge which is arcuate in cross section as indicated at 18 and this edge is concentric with the hinge pin 14 so that as the door is swung open or shut the bottom edge of the end wall of the bucket will scrape all concrete from the hinge edge, thus permitting the door to close without straining the hinge.

In order to close these doors a bar 19 is provided on each and this bar passes through the side angles 16 and the tee irons 17, projecting beyond the stiffening 16 on each side of the door. Attached to the bucket near the upper edge thereof are guide clips 20 through which extends the legs of a bail 21. The legs of the bail 21 are forked as at 22 and through these forked ends pass pins 23. One of the doors 15 has pivoted thereto links 24 which have their upper ends provided with a suitable perforation to receive the pins 23. The other door has pivoted thereto a pair of links 25 which have their upper ends slotted as at 26 to receive the pins 23.

The length of the links 24 is slightly less than the length of the links 25. When the bail 21 is pulled upward during the operation of hoisting, the doors 15 will be held in the position indicated in full lines

in Fig. 1. When, however, the bucket is set down for filling or transportation, the doors assume the position shown in dotted lines in Fig. 1 and the meeting edge of the door 5 which is fully closed will be scraped clean by the corresponding edge of the door which is slightly open. This movement is permitted by reason of the slotted connection 26 between the links 25 and the bail.

10 For the purpose of limiting the downward movement of the bail 21, this bail is provided with stop lugs 27 arranged to contact with the upper edge of the bucket.

Upon the upper part of the bail 21 is rigidly mounted a guide plate 28 through which passes a bar 29 having an eye 30 formed at the upper end thereof. The lower end of the bar 29 is rigidly attached to a fixed bail 31 which is rigidly mounted within the bucket, 20 the bail 31 and the bail 21 both lying in the same plane.

In using this bucket, the same is filled in the ordinary manner, the doors being held in the position shown in Fig. 1 either by placing 25 the bucket on the ground or by supporting the bucket from the bail 21. When it is desired to dump the bucket, the hoisting rope which is connected to the eye 30 is held taut while the rope connected to the bail 21 is 30 slackened off so that the bail 21 is permitted to drop along the bar 29 and the doors will then open. By reason of the bar 29 being rigidly connected to the bail 31 and supported at its upper end by the hoisting rope, the 35 bail 21 will be guided therealong so that no lateral movement of the upper portion of the bail will take place.

There has thus been provided a simple and efficient device of the character described 40 and for the purpose specified.

It is obvious that many minor changes may be made in the form and construction of the invention without departing from the material principles thereof. It is not, therefore, desired to confine the same to the exact form herein shown and described, but it is wished to include all such as properly come within the scope of the appended 45 claims.

50 Having thus described the invention, what is claimed as new, is:—

1. In a hoisting bucket, a body comprising side and end walls, doors hinged to said body and provided with hinge edges formed to constantly contact with the edges of the wall to which they are attached, and links connected to said doors and arranged to close one of said doors before the other is closed.

60 2. In a hoisting bucket, a body comprising side and end walls, doors hinged to said body and provided with hinge edges curved in an arc concentric with the center of the hinge and constantly contacting with the 65 respective edges of the wall to which they

are attached, and links connected to said doors and arranged to close one of said doors before the other is closed.

3. In a hoisting bucket, a body comprising side and end walls, a bail slidably mounted on said body, doors hinged to said body, links connecting said doors and bail, said links being arranged to close one of said doors before the other is closed, and a fixed bail mounted on said body. 75

4. In a hoisting bucket, a body comprising side and end walls, doors hinged to said body and provided with hinge edges formed to constantly contact with the edges of the wall to which they are attached, a bail slidably mounted on said body, links connecting said doors and bail, said links being arranged to close one of said doors before the other is closed, and a bail fixedly mounted on said body. 80

5. In a hoisting bucket, a body comprising side and end walls, doors hinged to said body and provided with hinge edges curved in an arc concentric with the center of the hinge and constantly contacting with the 90 edges of the respective walls to which they are attached, a sliding bail mounted on said body, links connecting said doors and bails, said links being arranged to close one of said doors before the other is closed, and a 95 fixed bail rigidly mounted on said body.

6. In a hoisting bucket, a body comprising side and end walls, doors hinged to said body, a sliding bail mounted on said body, links connecting said doors and bail and 100 arranged to close one of said doors before the other is closed, a fixed bail mounted on said body, a guide loop formed on said sliding bail, a bar rigidly attached to said fixed bail and extending through said guide loop, 105 and means on said bar to permit the attachment of a hoisting rope.

7. In a hoisting bucket, a body comprising side and end walls, doors hinged to said body provided with hinge edges formed to 110 constantly contact with the edges of the respective wall to which they are attached, a sliding bail mounted on said body, links connecting said doors and sliding bail, said links being arranged to close one of said doors before the other is closed, a fixed bail rigidly attached to the body, a guide loop formed on the sliding bail, a bar rigidly attached to the fixed bail and passing 115 through said guide loop, said bar being provided with means at its upper end to permit the attachment of a hoisting rope. 120

8. In a hoisting bucket, a body comprising side and end walls, a pair of doors hinged to said body, a sliding bail mounted 125 on the body, a pair of links connecting one of said doors to said bail, said links being pivotally attached to the doors and bail, a second pair of links pivotally attached to the other door and provided with slots at 130

their upper ends, and pivot pins passing through said slots connecting said links and sliding bail, said links being arranged to close one of said doors before the other is closed.

9. In a hoisting bucket, a body comprising side and end walls, a pair of doors hinged to the end walls and provided with hinge edges curved in an arm concentric 10 with the centers of the hinges and constantly contacting with the bottom edges of the end walls to which they are attached, a sliding bail mounted on said body, a pair of links pivoted to one of said doors, said links being 15 provided with pivot pin holes at the upper

ends, a second pair of links pivoted to the other door, said links being provided with slots at the upper ends, pivot pins passing through said pivot pin holes and slots to connect said links to the sliding bail, a fixed 20 bail provided with a rigid bar having an eye at the upper end thereof, and a guide loop mounted on the sliding bail and embracing said bar.

In testimony whereof, I affix my signature, in presence of two witnesses.

WILLARD D. LOCKWOOD.
